UNITED STATES PATENT OFFICE.

FERNANDO PROTHERO, OF MICHIGAN BAR, CALIFORNIA.

WHEEL.

SPECIFICATION forming part of Letters Patent No. 651,086, dated June 5, 1900.

Application filed September 19, 1899. Serial No. 730,992. (No model.)

To all whom it may concern:

Be it known that I, FERNANDO PROTHERO, a citizen of the United States, residing at Michigan Bar, in the county of Sacramento and State 5 of California, have invented certain new and useful Improvements in Wheels; and I do declare the following to be a full, clear, and exact description of the invention, such as will enable others skilled in the art to which it applies 10 to make and use the same, reference being had to the accompanying drawings, and to the letters and figures of reference marked thereon, which form a part of this specification.

15 My invention relates to that class of wheels which are adapted to be adjusted, with a view of taking up looseness and tightening their tires.

It consists in the strong and durable and 20 otherwise advantageous construction herein-after described, and particularly pointed out in the claim appended.

In the annexed drawings, Figure 1 is a longitudinal sectional view of the hub and felly 25 of my improved wheel. Fig. 2 is a section taken in the plane indicated by the broken line 2 2 of Fig. 1. Fig. 3 is a detached view of the joining ends of the felly, showing the clip thereon in section. Fig. 4 is a detail perspective view of the hub-body 5 of the improved wheel.

Similar letters and figures of reference indicate corresponding parts in the several views.

1 designates an axletree provided with a 35 spindle 2, of the usual form and function. On the inner end of the spindle 2 a collar 3 is rigidly fixed. The free end of said spindle 2 is fitted with screw-threads and has a nut 4 inserted thereon.

40 The hub of my wheel is formed of the cylindrical body 5, which is adapted to receive a box 7 within the same. The rear or inner end 6 of said body 5 is enlarged, as shown in cross-section, Fig. 1, and provided at suitable 45 intervals on the periphery thereof with apertures 8 for the reception of the ends of spokes 9. The outer end portion of the body 5 is exteriorly of rectangular form in cross-section and is provided with the alternate flat faces *a* and 50 rounded and threaded corners *b*, as best shown in Fig. 4. The flat faces *a* of the hub-body are designed for the engagement of the adjust-

able sleeve or section 10, which has a square bore, while the rounded and threaded corners *b* are designed for the engagement of a nut 55 11, through the medium of which the sleeve 10 is adjusted and adjustably fixed. The sleeve 10 has spoke-receiving apertures 8 in its periphery and is designed to be adjusted, as stated, for the purpose of forcing the spokes 60 outwardly, and thereby tightening the tire on the rim or felly. By virtue of the outer end of the hub-body 5 being of rectangular form in cross-section and the sleeve 10 having a square bore the strength of the hub-body is increased, 65 and at the same time the sleeve, while free to move endwise on the hub-body, is held against turning on said body, and is thereby enabled to securely retain the spokes in their proper relative positions. A nut 11, of suitable shape 70 and size, having screw-threads cut interiorly therein, is inserted over the outer end of the hub 5 6 and adapted to bear against the outer side of the sleeve 10. A lock-nut 12, which may have an ornamental closed end 13, may 75 be placed over the extreme end of the hub 5 6, so as to bear against the nut 11 for the purpose of maintaining the same in rigid position. A felly 14, having any suitable tire 15, may be placed in position over the free 80 ends of the spokes 9. The abutting ends of the felly 14 are secured in position by a clip 16 of ordinary external appearance, having a wedge-shaped lug 17 rigidly attached on the inner surface thereof. The lug 17 is 85 adapted to enter between the ends of the said felly 14 for the purpose of carrying a piece of leather 18 or other suitable material, which is adapted to fill the space between the ends of said felly when the same is pressed out 90 against the tire, as herein described. The lug 17 is adapted to be driven into place and the clip 16 attached in position by bolts 19, which may be inserted through slots in said clip 16. 95

The mode of operating my improved wheel is as follows: The box 7 is placed in the hub 5 6 in the usual manner and the sleeve 10 placed on the free or outer end of the body 5. The spokes 9 are then placed in position, 100 as usual, in the openings 8 therefor, said spokes being placed alternately in the enlarged end 6 of the hub and the sleeve 10, the outer ends thereof being engaged by a suit-

able felly 14, which is encompassed by a tire 15, of suitable material. The nut 11 is then placed in position over the end of the body 5 and against the sleeve 10, upon which said 5 nut is adapted to bear, pressing the same inwardly, which, as will be seen, presses the spokes 9 outwardly against the felly 14, causing the wheel to become extremely tight in every part. After the nut 11 has been im- 10 pelled against the sleeve 10 until all parts are tight the lock or jam-nut 12 is introduced over the end of the hub and engaged with the nut 11 for the purpose of maintaining the same in rigid position.

15 When applied to the axle, the operation is as in ordinary cases. The nut 12 13 is removed, the nut 4 placed on the end of the spindle 2, and the nut 12 13 replaced.

When the tire becomes loose from any 20 cause, the nut 12 13 may be removed and the nut 11 impelled against the sleeve 10 until the tire is tight. The nut 12 13 may then be placed in position against said nut 11.

Having thus described my invention, what

I claim as new, and desire to secure by Letters 25 Patent, is—

The combination of an axle-spindle having a threaded outer end, a nut mounted on said end of the spindle, a wheel comprising the hub-body arranged on the spindle, and having the enlargement 6 at its inner end provided with spoke-sockets, and also having the outer portion of angular form in cross-section provided with alternate flat faces *a* and rounded and threaded corners *b*, the sleeve 35 10, having the rectangular bore, arranged and adapted to slide on the rectangular outer portion of the body, and having spoke-sockets in its periphery, and a nut arranged on the outer end of the hub-body 5 and engaging the 40 threaded corners thereof, substantially as and for the purpose set forth.

In testimony whereof I affix my signature in presence of two witnesses.

FERNANDO PROTHERO.
